No. 749,041.

PATENTED JAN. 5, 1904.

W. DZINK.

WINDOW LOCK.

APPLICATION FILED SEPT. 5, 1903.

NO MODEL.

UNITED STATES PATENT OFFICE.

WLADISLAW DZINK, OF DUQUESNE, PENNSYLVANIA.

WINDOW-LOCK.

SPECIFICATION forming part of Letters Patent No. 749,041, dated January 5, 1904.

Application filed September 5, 1903. Serial No. 172,033. (No model.)

To all whom it may concern:

Be it known that I, WLADISLAW DZINK, a subject of the Emperor of Germany, residing at Duquesne, in the county of Allegheny and 5 State of Pennsylvania, have invented certain new and useful Improvements in Window-Locks, of which the following is a specification, reference being had therein to the accompanying drawings.

10 This invention relates to certain new and useful improvements in locks, and relates particularly to locks adapted for use in connection with windows for locking the sash in the closed or partially-open position and acting also to support the window-sash in lieu 15 of the ordinary cords and weights.

Briefly described, the invention comprises a substantially L-shaped casing, in the shorter leg of which is pivotally hung a latch for engagement with a catch carried in the window-frame. This latch is pivotally connected to a rod which works in the longer leg of the casing and which rod has a projection protruding through a slot in the front wall of 25 the casing, and to this projection is pivoted a handle by means of which the rod may be operated to retract the same to disengage latch from the catch. The latch is held normally projected in its locking position by 30 means of a spring, and means is provided for holding the latch retracted when desired.

The above construction will be hereinafter more specifically described and set forth in detail, and in such description reference will 35 be had to the accompanying drawings, forming a part of this application, and wherein like numerals of reference will be employed for designating like parts throughout the different views, in which—

40 Figure 1 is a front elevation of a window and window-frame, showing my improved lock in position thereon. Fig. 2 is a transverse vertical sectional view of the window-frame. Fig. 3 is a partial side and partial 45 longitudinal section of the lock. Fig. 4 is a horizontal sectional view taken on the line 4 4 of Fig. 3. Fig. 5 is a front view with the casing partly in section to show the pivot of the latch. Fig. 6 is a transverse vertical 50 sectional view taken on the line 5 5 of Fig. 4, and Fig. 7 is a detached detail perspective

view of one of the catches; and Fig. 8 is a sectional view of a part of the upper sash, showing how the lock is mounted therein.

To put my invention into practice, I provide a substantially L-shaped casing, the longer leg 1 of which and the shorter leg 2 are preferably formed integral with each other, the casing being cast for convenience in manufacture. At its inner end the longitudinal leg 1 of the casing is provided with an apertured lug 3, and the vertical leg 2 is provided at its upper and lower ends with like apertured lugs 4, these lugs being adapted to receive securing means, such as screws, for fastening the casing in position. The casing is countersunk in the sash-rails, the outer face of the longitudinal leg 1 being flush with the outer face of the lower rail of the sash and the face-plate of the vertical leg 2 being flush 70 with the face of the sash-rail that is adjacent to the window-frame. Pivoted in the upper part of the vertical leg 2 and projecting through an opening 5 in the front plate of said leg is a latch 6, which is shouldered 75 off near its lower end and has pivotally connected to this shouldered-off portion the outer end of the operating-rod 7. This operating-rod is guided by a slotted integral web 8 and carries an angular lug 9 on its rear end, to 80 which is pivoted a handle 11, that extends through a slot 10, provided therefor in the front plate of the casing. At the ends of the slot 10 are notches 10' 11', respectively, into which the handle 11 is engaged for locking the latch 6 in the retracted and projected positions. The latch is retained normally in the engaging position by means of a spring 14, arranged on the rod 7 between the web 8, and an integral collar 15, carried by said rod. 90 The side walls of the shorter leg of the casing are provided with bosses 16, as shown in Fig. 5, which gives greater bearing-surface for the pivot-pin 17 and also prevents lateral movement of the latch. Countersunk in the rails 95 of the frame 18 are the catches 19 to be engaged by the latch for supporting the sash in the open position.

The casing and lock just described are designed particularly for use on the lower sash, 100 and for the upper sash I employ the same form of lock, the only difference in construc-

tion being that I provide the casing 1' in its upper face with a slot 2' to receive the pivoted handle 11, which is engaged in a notch 3' at the rear end of the slot when it is desired to hold the latch 6 and rod 7 in the retracted position. This casing is constructed in this manner, so that the projecting handle 11 will not interfere with the raising of the lower sash or the lowering of the upper sash. It will be observed that only the one notch 3', that for holding the rod 7 retracted, is required in the casing for the upper sash, as when the window is closed or in the raised position it cannot be further raised. With the lower-sash lock, however, the engaging of the handle in the notch 11' holds the latch in the projected position, and consequently prevents the lifting of the lower sash until the rod and latch are retracted.

Having fully described my invention, what

I claim as new, and desire to secure by Letters Patent, is—

A window lock and support, comprising a substantially L-shaped casing open on one side and provided in one face with a slot, a latch pivotally hung in the shorter leg of the casing, an operating-rod in the longer leg of said casing and pivotally connected to said latch, a spring on said rod for holding the latch normally in the projected position, and a handle pivoted to the rear end of the operating-rod and projecting through the slot in the casing, substantially as described.

In testimony whereof I affix my signature in the presence of two witnesses.

WLADISLAW DZINK.
